UNITED STATES PATENT OFFICE.

WILLIAM H. PERRY, OF CONCORD, NEW HAMPSHIRE.

DESIGN FOR A MONUMENT.

SPECIFICATION forming part of Design No. 28,125, dated January 4, 1898.

Application filed November 22, 1897. Serial No. 659,524. Term of patent 14 years.

To all whom it may concern:

Be it known that I, WILLIAM H. PERRY, a citizen of the United States, residing at Concord, in the county of Merrimac and State of New Hampshire, have invented and produced a new and original Design for Monuments; and I do hereby declare the following to be a full, clear, and exact description of the invention, such as will enable others skilled in the art to which it appertains to make and use the same.

My design consists, essentially, in the particular shape and configuration of the shaft and its ornamental top or cap, together with the character of finish used upon the several parts, as fully set forth in the following specification and claim and clearly illustrated in the drawing accompanying and forming a part of the same, in which—

1 represents the oblong base, having four vertical sides and terminating in an obtuse frustum 2 of a pyramid.

3 is the pedestal, and 4 an acute frustum of a pyramid, which joins the top of the pedestal, and on one or more sides of said frustum 4 may be formed a raised tablet 5, forming a convenient place for placing an inscription.

From the frustum 4 rises the shaft 6, which is also oblong, having four vertical sides, each being provided with a tablet 7, distinguishable by a surface of a different character and the heavy border-lines 8.

The top or cap of the shaft projects on all sides thereof, curving therefrom upward and outward, as at 9, the vertical portions 10 meeting the lower edge of the pyramid top portion 11, which is ornamented on each of its four corners by raised semicircular tapering tablets, tapering toward the apex of the top 40 11, the lower portion of which tablets represent overlapping portions 12, while the upper portions 13 are fluted. One or both of the longest sides of said top 11 may be provided with raised tablets 14 and 15, the former 45 being similar to the lower portions 12 of the corner tablets and the latter being flat with vertical sides and arranged one at each side of the tablet 14 and all tapering to the apex of the top 11.

The style of finish for the various parts is designated by reference-letters, A representing rockwork, B hammered work, and C polished work.

Having thus described my design, what I 55 claim is—

The design for a monument substantially as herein shown and described.

In testimony whereof I affix my signature in presence of two witnesses.

WILLIAM H. PERRY.
